UNITED STATES PATENT OFFICE.

BENJAMIN W. TUCKER, OF NEWARK, NEW JERSEY, ASSIGNOR TO JOHN BEECHER PATTON, OF KENT, OHIO.

TACKING DEVICE.

1,093,300.

Specification of Letters Patent. Patented Apr. 14, 1914.

Original application filed February 14, 1906, Serial No. 301,072. Divided and this application filed March 3, 1906. Serial No. 304,080.

To all whom it may concern:

Be it known that I, BENJAMIN W. TUCKER, a citizen of the United States, and a resident of Newark, in the county of Essex and State of New Jersey, have invented 5 certain new and useful Improvements in Tacking Devices, of which the following is a full, clear, and exact description.

This invention relates more particularly 10 to a tacking device for a machine such as is disclosed in Reissue Patent No. 12,445, granted to Ephraim O. Engberg, February 6, 1906, and is a division of Patent No. 976,646, granted to me Nov. 29, 1910.

15 The primary object of the invention is to provide simple and efficient means whereby one or more tacks may be automatically collected and properly held in position, and the said tacks forced into a shade-roller to fasten 20 the shade material thereto.

A further object of the invention is to provide simple and efficient means whereby the material may be automatically forced around the shade-roller into tacking position and to brace the shade-roller during the 25 tacking operation.

The invention will be hereinafter more particularly described with reference to the accompanying drawings, which form a part 30 of this specification, and will then be pointed out in the claims at the end of the description.

Figure 1 is a vertical longitudinal section of one form of device embodying the invention, showing how the device may be applied to a window shade machine, only a part of which is illustrated. Fig. 2 is a partial side elevation. Fig. 3 is a detail view of the means for intermittently rotating the tacking 40 collecting device. Fig. 4 is a sectional plan view of the device. Fig. 5 is a front elevation. Fig. 6 is an enlarged fragmentary front view, partly in section and partly in elevation, of the means for tacking the material to the shade-roller, the section being taken on the line VI—VI of Fig. 7. Fig. 7 is a vertical section taken on the line VII—VII of Fig. 6; and Fig. 8 is a section on the line VIII—VIII of Fig. 7, showing the 45 chute and vibratory bottom of the hopper for agitating the tacks.

While I have shown the tacking device as applicable to fastening shade material to the

usual roller, it will be understood that said device may be used in other relations, and 55 for other purposes, and that some of the parts may be dispensed with, or others substituted therefor, without departing from the character of the invention.

The shade-roller holding means is located 60 at the front of the machine and is adapted to removably hold the shade-roller 20. Adjacent to the shade-roller holding means is a transverse brace or bar 21 to which are secured a series of strips or plates 22 that 65 extend inward and are adapted to support and guide the shade material as it is fed in position to be fastened to the shade-roller. The shade-roller 20 is supported by a spring-pressed center or device 23 which is slidingly 70 held in the bearing 24, said bearing being adjustable along a support or slide 25. A chuck 26 supports the other end of the shade-roller and is provided with projections to engage and rotate said roller. The 75 chuck and its shaft or spindle 27 may be also made adjustable transversely if desired, said spindle being journaled in bearings 28 and 29. On the end of the spindle 27 is a grooved pulley 30 which is rotated by a belt 80 31, the said belt being adapted to slip when the material is wound tight on the roller. The parts just described are substantially 85 the same as in the patent and application referred to.

As shown the material is adapted to be fastened to the shade-roller by a single movement of a part of the machine. The support or slide 25, Figs. 1, 6 and 7, is held to move vertically in guides on the machine 90 frame 32, and entering recesses in the support are the ends of the levers 33, which are pivotally held to the shaft 34, and have their other ends connected to rods 35. The lower ends of the rods 35 are fastened to a treadle 95 36, by which the work support 25 is raised when the forward end of said treadle is depressed, a spring 37 being provided to assist in restoring the treadle to its former position. On the support or slide 25 is the adjustable bracket 38 in which the bearing 24 is vertically movable, and a second bracket 39 in which the bearing 28 is vertically movable. A third bracket 40 is secured to one end of the support 25 in which the bearing 29 is vertically movable. The bearings 100 105

24, 28 and 29 carry the shade-roller holding means, and each bearing is normally forced downward in its bracket by a spring 41. Beneath the shade-roller is a shaft 42, along 5 which are a series of anvils or braces 43. These braces are adjustable along the support 25 by the bolts or screws 44 and have projecting ends to hold and guide the forward end of the shade preparatory to fastening it to the shade-roller. To the shaft 42 are fastened a series of curved fingers 45, adapted, when the shaft is rotated, to force the end of the shade around the roller into fastening position. The ends of the 10 shaft 42 are held in brackets on the support 25, and on each end of the shaft is a segmental gear 46, which is adapted to mesh with the teeth of racks 47, fastened to the fixed bar 21, so that the support 25 when 15 moved vertically, will rotate said shaft. Each gear 46 has a foot 48, which is adapted to engage and slide along a straight part of its rack during the upward movement of the support and as soon as the gears are 20 disengaged from the racks. This holds the fingers 45 in a raised position and until the gears again engage the racks as the support 25 is lowered, thereby releasing the fingers and forcing them downward. In the path 25 of the bearing 29 is a bolt 49 which is held in a fixed bracket 50 and is adapted to engage the bearing 29 when the support 25 is lowered. The purpose of this bolt is to raise the spindle 27, the shade-roller 20 and 30 the connections above the braces or anvils 43 to permit the shade-roller to rotate and wind the shade thereon and to permit the forward end of the next shade to be fed beneath the shade-roller and over the braces 35 and the fingers. A second stop or bolt may also be provided to raise the bearing 24 and to work in connection with the bolt 49. By this means a brace is provided under the shade-roller at each point where a tack is to 40 be driven into said roller, and the forward end of the shade is automatically forced around the roller ready for tacking.

The shade-roller as it is raised by the lifting of the support 25 is moved toward a 45 collecting or receiving device 51. This device may be of any suitable form. As shown the device is rotary and comprises a series of radial permanent magnets 52. These magnets form arms and are fastened to a 50 sleeve 53 which is held to rotate in a frame 54. The sleeve is splined as to slide along the shaft 55, there being a series of such devices and frames according to the number of tacks to be driven into the shade-roller. The 55 shaft 55 and tack-collecting device 51 rotate intermittently, and the separate arms or magnets are successively brought to a point adjacent to a tack-conveying chute 56 forming a continuation of a hopper 57. This 60 hopper is loosely supported on a shaft 58,

and at its forward end is loosely held on a shaft 59. There is a hopper for each collecting or receiving device 51 and both hopper and device are movable together with the frame 54, which latter is adjustably held 70 to the transverse bar 60 by the bolts 61. To the shaft 59 is fastened a collar 62 for each hopper, and to the collar is fastened the plate 63 forming the bottom of the hopper. An arm 64 is held on the shaft 59 at one end, 75 and in the path of said arm is a rotary star or toothed wheel 65 fastened to the shaft 58. The shaft 58 has a pulley 66 fastened thereto, which is driven by a belt 67 from a suitable drive pulley, so that as the shaft 80 85 90 95 100 105 110 115 120 125 130 135 140 145 150 155 160 165 170 In operating the invention the tacks in the hoppers 57 are agitated so as to pass down the chute 56, the inturned end of each chute serving to hold and position the 5 lowermost tack of the row. The hoppers are now moved on the shaft 59, thus throwing the lower ends of the chutes against the stops 75. This will raise the yielding member 69 of each chute and will release the 10 lowermost tack, the remainder of the row of tacks being temporarily held by the part 76 of the stop. The hopper is now swung in the opposite direction toward the device 51 and in the path of one of the magnet 15 arms. One arm of each device will take and hold a tack so that the chute may again be moved away from the device and the influence of the magnets. Rotary motion is now imparted to the device 51, to carry a 20 line of tacks into the path of vertical movement of the support 25 and the shade-roller. The shade material having been forced around the roller by the fingers 45 as already described, the treadle 36 is depressed 25 which will force the support 25 and shade-roller upward, thereby forcing the tacks through the material and securely fastening the end of the shade to the roller.

Where the mechanism for tacking is used 30 separately from the shade machine proper, the tack collector may be operated directly from the treadle, and this as well as some of the other features, may be timed with respect to the movement of the work support 35 25.

It will be understood that the anvils or braces 43, as well as some of the other parts, may be used in connection with attaching or fastening other work than window shades; 40 that the tacks or fastening means may be positively delivered to a tack-holding device instead of depending in part on magnetism; and that other fastening devices than tacks may be used when desired.

Having thus described my invention, I claim as new and desire to secure by Letters Patent:—

1. In a machine of the character described, the combination with a support, of a hopper 50 adjustably mounted on said support and adapted to hold tacks *en masse*, means for agitating the tacks, a rotary tack collecting device movably mounted below the hopper, means for conveying the tacks from the hopper to a point adjacent to the tack collecting device, and means whereby the tacks may be fed singly to said tack collecting device.

2. The combination with a support, of a 60 series of hoppers adjustably mounted on said support and adapted to hold tacks, means for agitating the tacks, a series of rotary tack collecting devices movable with the hoppers, means for conveying the tacks 65 from the hoppers to a point adjacent to the

tack collecting devices, together with means whereby the tacks may be fed singly to said tack collecting devices.

3. The combination with a support, of a 70 tack holding device, a pivotably held hopper, means for agitating the tacks in the hopper, a chute comprising a fixed and a yielding member for conveying the tacks to the tack holding device, means for moving the hopper on its pivot to carry the lower 75 end of the chute away from said device, and a stop or projection for raising the yielding member and releasing one tack at a time for delivery to said tack holding device.

4. The combination with means for supporting shade material, of a support, a plurality of movable devices adapted to hold fastening elements and located on the support, means for permitting individual adjustment of said devices, supporting means for a shade-roller, and means for imparting a vertical movement to the shade-roller supporting means whereby the series of devices may be made to simultaneously force a plurality 80 of fastening elements into the shade-roller to fasten the shade material thereto.

5. The combination with means for supporting shade material, of a shaft, a plurality of movable devices adapted to hold 95 fastening elements and located on the shaft, a backing for a shade-roller, and means for moving the shade roller toward the devices whereby the series of devices may be made to simultaneously force a plurality of the 100 fastening elements while held by said devices into the shade-roller to fasten the shade material thereto.

6. The combination with means for supporting shade material, of a shaft, a plurality of movable devices adapted to hold fastening elements, means for permitting the individual adjustment of said devices along the shaft, a support for a shade-roller, and means for moving the support and 105 shade-roller toward the devices whereby the series of devices may be made to simultaneously force a plurality of the fastening elements while held by said devices into the shade-roller to fasten the shade material 110 thereto.

7. The combination with a work support adapted to hold a shade-roller, of means for supporting shade cloth, anvils mounted on the support and adapted to engage the 115 shade-roller, movable fingers adapted to force the shade-material about the shade-roller, a movable device carrying the fastener, and means for operating the parts.

8. The combination with a movable work 125 support adapted to hold a shade-roller, of means for supporting shade material, anvils mounted on the support adapted to engage the shade-roller, movable fingers adapted to force the material around the 130

- shade-roller, a movable tack-holding device, a hopper, together with means for delivering the tacks to the said tack-holding device.
5. 9. The combination with a vertically movable work support, of means for supporting a shade-roller on said support, means for raising the shade-roller supporting means relatively to the support when the latter is in a certain position, and means for tacking the material to the shade-roller.
10. 10. The combination with a vertically movable work support, of means for supporting a shade-roller on said support, means for raising the shade-roller supporting means relatively to the support when the latter is in a certain position, devices for forcing the material around the roller in tacking position, and means for tacking the material to the shade-roller.
15. 11. The combination with a vertically movable work support, of means for yieldingly holding a shade-roller on said support, a plurality of devices carried by the work support and adapted to engage the shade-roller at the tacking points, and means for tacking the material to the shade-roller.
20. 12. The combination with a frame, of a support vertically movable on said frame, shade-roller holding means mounted upon said support and movable relatively with respect thereto, a plurality of fingers carried by the support, means for rotating the fingers to throw the material around the shade-roller in tacking position, together with means for tacking the material to the shade-roller.
25. 13. The combination with a frame, of a support vertically movable on said frame, shade-roller holding means mounted upon said support, a plurality of fingers carried by the support and movable therewith, means for rotating the fingers to throw the material around the shade-roller in tacking position, together with means for tacking the material to the shade-roller.
30. 14. The combination with a frame, of a support vertically movable on said frame, shade-roller holding means mounted upon said support, a plurality of fingers carried by the support adjacent to the shade-roller holding means, means for rotating the fingers to throw the material around the shade-roller in tacking position, a plurality of anvils carried by the support and adapted to engage the under surface of the shade-roller, together with means for tacking the material to the shade-roller.
35. 15. The combination with a frame, of a support vertically movable on the frame, shade-roller holding means yieldingly held on said support and relatively movable with respect thereto when said support is in a predetermined position, means whereby the shade-roller holding means may be moved relatively to the support, anvils adjustably held on the support and adapted to engage the shade-roller, a plurality of fingers rotatably held on the support, means for rotating the fingers to force the material around the shade-roller, and a plurality of tacking devices adapted to force a series of tacks through the material into the shade-roller on movement of the support, and means for moving the support toward the tacking means.
40. 16. The combination with a frame, of a support movable on the frame, shade-roller holding means held on said support, anvils adjustably held on the support and adapted to engage the shade-roller, a plurality of fingers rotatably held on the support, means for rotating the fingers to force the material around the shade-roller, and a plurality of tacking devices adapted to force a series of tacks through the material into the shade-roller on movement of the support, and means for moving the support toward the tacking means.
45. 17. The combination with a frame, of a support movable on the frame, shade-roller holding means relatively movable with respect thereto when said support is in a predetermined position, means whereby the shade-roller holding means may be moved relatively to the support, anvils adjustably held on the support and adapted to engage the shade-roller, a plurality of fingers rotatably held on the support, means for rotating the fingers to force the material around the shade-roller, and a plurality of tacking devices adapted to force a series of tacks through the material into the shade-roller on movement of the support, and means for moving the support toward the tacking means.
50. 18. The combination with a frame, of a support vertically movable on the frame, shade-roller holding means held on said support, anvils adjustably held on the support and adapted to engage the shade-roller, and a plurality of tacking devices adapted to force a series of tacks through the material into the shade-roller on movement of the support, and means for moving the support toward the tacking means.
55. 19. The combination with a work support, of a plurality of independent and rotary tack-collecting devices, a plurality of hoppers one for each collecting device, means for pivoting the hoppers so that they may move simultaneously toward and away from the tack-collecting devices, a movable bottom in each hopper for agitating the tacks, means whereby said bottom may be vibrated, and a chute leading from each hopper to a point adjacent to the tack-collecting device.
60. 20. The combination with a work support, of a plurality of independent and ro-

- 5 tary magnetic tack-collecting devices, a plurality of hoppers one for each collecting device, a frame supporting the hoppers and collecting devices in pairs, means for pivoting the hoppers so that they may move simultaneously toward and away from the tack-collecting devices, and a chute leading from each hopper to a point adjacent to the tack-collecting device.
- 10 21. The combination with a frame, of a support thereon, a plurality of frames adjustable along the support, a rotary tack-collecting device supported in each frame and adjustable therewith, a tack hopper pivotally supported in each frame and also adjustable therewith, means for agitating the tacks in the hopper, a chute comprising a fixed and a movable member leading from each hopper to a point adjacent to the tack-collecting device, one of said members of the chute having a projecting end, a stop carried by each frame and adapted to engage the end of the movable member so as to release a tack, a projection carried by the stop and adapted to prevent the release of but one tack at a time, means for moving the hopper and chute on its pivot to release the tacks in succession and to permit the tack-collecting device to remove the tacks singly from the chute, shade-roller holding means on the frame together with means for forcing the shade-roller holding means toward the tack-collecting device for forcing the tacks into the shade-roller.
- 15 22. The combination with a support, of a frame adjustable along the support, a tack-collecting device supported in the frame and adjustable therewith, a tack hopper pivotally supported in the frame and also adjust-
- able therewith, means for agitating the tacks in the hopper, a chute comprising a fixed and a movable member leading from each hopper to a point adjacent to the tack-collecting device, a stop carried by the frame and adapted to engage the end of the chute member so as to release a tack, a projection adapted to provide for the release of but one tack at a time, and means for moving the hopper and chute on its pivot to release the tacks in succession and to permit the tack-collecting device to remove the tacks singly from the chute.
- 20 23. The combination with a frame, of a support thereon, a plurality of frames carried by the support, a tack-collecting device supported in each frame, a tack hopper pivotally supported in each frame, means for agitating the tacks in the hopper, a chute comprising a fixed and a movable member leading from each hopper to a point adjacent to the tack-collecting device, a stop carried by each frame and adapted to engage the chute member so as to release a tack, a projection carried by the stop and adapted to provide for the release of but one tack at a time, means for moving the hopper and chute on its pivot to release the tacks in succession and to permit the tack-collecting device to remove the tacks singly from the chute, and shade-roller holding means on the frame, together with means for forcing the shade-roller holding means toward the tack-collecting devices for forcing the tacks into the shade-roller.
